carries a resilient sealing member 58 for the purpose of preventing leakage between the bores 32 and 56.

The bore 32 communicates with the inlet of a ball check valve 59 comprising the ball 60 and spring 62 by a bore 64 in the pump body. The discharge side of the said check valve communicates by a passage 66 with the lower end of the bore 56. The bore within which the ball 60 slides is preferably fluted as indicated at 68 to permit fluid flow around the said ball when it is lifted from its seat.

The body 26 also comprises a second check valve generally indicated at 70, the inlet of which communicates by a passage 72 with a port 74 in the lower end of the bore 56, and whose outlet communicates directly with the discharge conduit 12.

In operation, the lever 48 is first moved to bring the pistons into their Figure 2 position. Thereafter a pumping stroke is accomplished by moving the lever 48 counterclockwise about its pivotal support on the plate 22. As the plunger 40 moves downwardly, the portion 54 thereof displaces fluid from the bore 56 through the passage 72 and check valve 70 to the discharge conduit 12. When the abutting means 44 on the plunger 40 engages the piston 34 and the said piston begins to move with the plunger 40, then fluid is also displaced from the bore 32 through the check valve 59, passage 72, and check valve 70 to the discharge conduit 12.

On the return stroke of the piston and plunger, the plunger first moves upwardly sufficiently far to uncover the grooves 42. Thereafter, the plunger 40 and piston 34 move together with the fluid required to fill the cavities beneath the plunger and piston flowing thereto through the grooves 42 from the reservoir 20.

As long as the fluid circuit being supplied requires only low pressure, the lever 48 can be reciprocated between the limits necessary to actuate the piston 34. However, when the pressure requirements of the circuit increase, then the resistance to movement of the piston 34 increases and the pump operator will commence oscillating the lever 50 between its Figure 1 position and the position wherein the abutting means 44 strikes the top of the piston 34. When the lever is being so oscillated, only the portion 54 of the plunger 40 is displacing fluid while the check valve 59 prevents the high pressure fluid from standing on the piston 34.

It will be noted that the pump has two rates of displacement, one when both the piston 34 and plunger 40 are displacing fluid to the discharge conduit, and another when only the plunger 40 is displacing fluid. It will be apparent that the two rates of discharging fluid can be governed by the relative sizes of the said plunger and piston, and that a correspondingly higher pressure can be developed on the pumped fluid by the plunger 40 than by the piston 34 with the same exertion on the handle 50.

The arrangement shown in Figure 5 is similar to that shown in Figures 1 through 4 and is identified by similar numerals with the addition of a subscript *a*.

The difference in the construction of Figure 5 is principally that of relocating the discharge check valve 70a so that it is in axial alignment with the plunger 40 thereby simplifying the machining of the body 26a. Also, in Figure 5, the movable members in the check valves 59a and 70a are conically shaped valve members rather

than balls, this difference being essentially one of design rather than function or of principle.

In Figure 5 there is also shown a sealing member 88 which is adapted for being engaged by the abutting means 44a when the plunger 40a is moved downwardly to pick up the piston 34a. By the sealing member 88, leakage of fluid from the cylinder 32a back to the reservoir is substantially prevented, while the resiliency of the said member absorbs the shock of the abutting means 44a when it meets the said piston.

It will be apparent that this invention provides for a simple pumping structure which is easily manufactured and assembled and which has relatively few working parts. The pump is adapted for discharging fluid at a plurality of rates of flow and at a plurality of pressures. The several rates of flow are obtained by a single operating lever by oscillating the same between different limits of travel.

It will be understood that this invention is susceptible to modification in order to adopt it to different usages and conditions and, accordingly, it is desired to comprehend such modifications within this invention as may fall within the scope of the appended claims.

We claim:

1. In a pump; first and second pumping means having different displacements; a single actuating means for said pumping means selectively operable to actuate the smaller thereof independently or both thereof simultaneously; means of supplying fluid to be pumped to said pumping means; valve means permitting the flow of fluid from the larger of said pumping means to the smaller but not vice versa; and other valve means permitting the flow of fluid from the smaller of said pumping means to a discharge.

2. In a pump; a larger and a smaller pumping means; a single actuating means for said pumping means operable to actuate the smaller thereof independently or both thereof simultaneously; means of supplying fluid to be pumped to said pumping means; a check valve opening from the larger of said pumping means to the smaller; and another check valve opening from the smaller of said pumping means to a discharge.

3. In a pump; a pump body; a large and a small fluid displacing means within said body; a single actuating means for said pumping means mounted on said body and movable between first predetermined limits for actuating only the smaller of said pumping means; and between said second predetermined limits for actuating both of said pumping means simultaneously; a discharge port in said body; a first check valve opening from said smaller pumping means to said discharge port; and a second check valve opening from the larger of said pumping means into the smaller.

4. In a pump; a first piston and cylinder; a second piston passing through said first piston and extending into a second cylinder; an actuating means connected with said second piston for reciprocating the same; abutment means on said actuating means for abutting and actuating said second piston during a predetermined portion of the movement of said actuating means; a check valve opening from said first cylinder into said second; another check valve opening from said second cylinder to a discharge port and means of supplying fluid to be pumped to said cylinders.

5. In a pump; a first piston and cylinder; a second piston extending through said first piston and into a second cylinder; abutment means lim-

iting the relative movement of said pistons; a flow passage extending between said pistons and adapted to be interrupted when said second piston engages the first thereof in its pumping direction of movement; a check valve opening from said first cylinder into said second cylinder; another check valve opening from said cylinder into a discharge; and a single actuating means connected with said second piston.

6. In a pump; a pump body having a first cylinder; a first piston in said first cylinder; yielding means continuously urging said first piston into inoperative position; a second cylinder; a second piston in said second cylinder and extending through said first piston; an actuating means for reciprocating said second piston; abutment means carried by said actuating means for engaging said first piston when the second thereof has moved a predetermined distance in its pumping direction; a flow passage extending from said first cylinder to the space above said first piston and adapted for being interrupted when said first piston is engaged by said abutment means; and independent check valves between the discharge side of said pump and said cylinders.

7. In a pump; a pump body having a discharge port; a first cylinder bore in said body; a first piston in said first bore; yielding means continuously urging said first piston toward a position of greatest volume of said bore; a second cylinder bore in said body; a second piston in said second bore; actuating means for said second piston extending through said first piston and adapted for engagement with said first piston in at least the pumping direction of movement of said second piston; a flow passage extending along said actuating means for connecting said first cylinder bore with the space above said first piston and adapted for interruption when said abutment means engages said first piston; a 40 check valve opening from said first cylinder bore into said second; and a second check valve opening from said second cylinder bore into said discharge port.

8. In a pump; telescoping piston means of different diameters; individual cylinder means for receiving said pistons; a check valve opening from the larger of said cylinders into the smaller, and another check valve opening from the smaller of said cylinders to a discharge; a flow passage extending along the telescoping parts of said pistons and adapted for being interrupted in response to the movement of the inner thereof a predetermined amount in its pumping direction; means operable thereafter to connect said pistons together for the simultaneous movement thereof; and an actuating means for said pistons comprising a pivoted lever connected with the said inner piston.

10 9. In a pump; first and second telescoping pistons; first and second cylinders within which said pistons are reciprocable; yielding means continuously urging the larger of said pistons in a direction opposite to its pumping direction; a single actuating means for reciprocating the smaller of said pistons independently between predetermined limits, or both of said pistons simultaneously between other predetermined limits; passage means for supplying fluid to be pumped to said cylinders extending through the larger of said pistons; a discharge passage for said first cylinder including a check valve opening from said first cylinder into the second thereof; and a discharge passage for said second cylinder comprising a check valve opening from said second cylinder to a discharge port.
